UNITED STATES PATENT OFFICE.

JOHN STOGDELL STOKES, OF PHILADELPHIA, PENNSYLVANIA, ASSIGNOR TO STOKES & SMITH COMPANY, OF SUMMERDALE, PENNSYLVANIA, A CORPORATION OF PENNSYLVANIA.

SEALED CONTAINER.

1,152,354.

Specification of Letters Patent. Patented Aug. 31, 1915.

Application filed April 24, 1914. Serial No. 834,049.

To all whom it may concern:

Be it known that I, JOHN STOGDELL STOKES, a citizen of the United States, residing at Philadelphia, in the county of 5 Philadelphia and State of Pennsylvania, have invented new and useful Improvements in Sealed Containers, of which the following is a specification.

This invention relates to sealed packages 10 or containers, and the invention is especially useful where the contents of a box is to be wrapped and sealed, so as to substantially exclude the air.

A principal object of the invention is to 15 provide a container, the body of which is of a common form, but having a wrapper of a particular form, and applied to the box in a very simple manner so as to form a cover which completely envelops and seals 20 the box.

In the drawing, which illustrates one embodiment of my invention, Figure 1 is a perspective showing the bottom section of a box of common form. Fig. 2 is a perspective 25 showing the construction of the box. Fig. 3 is a perspective showing the end of a box of another form, which is closed at an end wall. Fig. 4 is a vertical section through a box having the parts shown in Figs. 1 and 30 2, and enveloped in my sealing cover. Fig. 5 is a vertical section through the end of a box of the construction shown in Fig. 3, and with my sealing cover applied. Fig. 6 is a plan of a blank, which I prefer to employ in forming the sealed container.

Referring more particularly to the parts, 10 and 11 represent respectively, the bottom section and the cover section of a box of common form, the bottom section having 40 side walls 12 and end walls 13, and the cover section 11 being similarly formed with side walls 14 and end walls 15. The cover section is slightly larger than the bottom section, so as to be applied over the same tele- 45 scopically. The side walls of both sections are of substantially the same dimensions so that when these parts are put together a narrow gap or space 16 is formed around the bottom 17 of the box. This bottom 17 50 and the top wall 18 of the box form the main walls of the container. The cover for sealing the box is preferably of the form illustrated in Fig. 6 and comprises a sub- 55 stantially rectangular body portion 19 hav- ing integral side flaps 20 and integral end

flaps 21. The side flaps are adapted to fold on the body portion at the dotted lines 22, while the end flaps 21 are adapted to fold at the points indicated by the dotted line 23. One pair of these flaps, preferably side flaps 20, is provided with end laps 24, which are integral and which are adapted to overlap the corners of the wrapper on the side edges of the box when the wrapper has been applied thereto. All of the flaps are provided with marginal portions 25. In applying the wrapper to the box 4 the body portion 19, which is of the same dimension and shape as any selected wall of the box, preferably one of the main walls, is applied to 60 the corresponding wall of the box, and the flaps 20 and 21 are then folded over so as to cover the side and the end walls of the box, but the end laps 24 are first folded over the adjacent box ends. And the marginal 65 portions 25 are then folded over the edges of the opposite main wall. As illustrated in Fig. 4 the body portion 19 is applied to the upper wall 18, in which case the marginal portions extend across the space 16 and seal 70 it. If desired the entire area of the wrapper can be attached to the box by an adhesive, but if desired the adhesive may be applied only on the end laps 24 and on the marginal 75 portions which seal the space 16. If desired 80 the body portion 19 could be applied to the bottom wall 17 of the box instead of to the top wall, so that the marginal portions 25 of the cover would be attached to the edges 85 of the wall 18. 90

In order to give the box a neat appearance I prefer to cover the wall to which the marginal portions 25 are attached by means of a facing piece 26, which preferably consists of a single sheet of rectangular form 95 conforming in dimensions to this wall of the box. This sheet 26 preferably extends over the marginal portions and is attached to them by an adhesive, and also to the wall of the box preferably throughout the entire 100 area of the sheet.

It is evident that a box of the form shown in Fig. 3 can be wrapped and sealed in the same manner as the box illustrated in Fig. 4, the preferred arrangement of the parts 105 of the box and cover being illustrated in Fig. 5.

The box illustrated in Fig. 3 is a common form particularly adapted to be made from a carton and having its end closed by 110

an end wall 27 having a hinged movement at 28, and a flap 29, which overlaps a wall 30 opposite the edge 28. Such boxes sometimes have side flaps on the edges 31 which overlap the adjacent walls.

It is understood that the embodiment of the invention described above is only one of the many forms or embodiments the invention may take, and I do not wish to be limited to the practice of the invention, nor in my claim, to the particular embodiment set forth.

What I claim is:—

As a new article of manufacture, a sealed-wrapped package comprising a box and a wrapper-blank enveloping and adherently attached to the exterior walls of the box, said wrapper comprising a body portion and integral side and end wings, said body portion being adherently attached to a selected wall of the box and the said side and end wings being adherently attached respec-

tively to the side and end walls of the box, the said side and end wings being provided with marginal lap portions overlying and adherently attached to the marginal edges of the wall of the box opposite the said selected wall, and a separate wall covering label having substantially the dimensions of the said selected wall, said label overlying and adherently attached to the said marginal lap portions and to the wall of the box opposite said selected wall, the construction and arrangement being such as to provide a sealed-wrapped package having a smooth exterior.

In testimony whereof I have hereunto set hand in presence of two subscribing witnesses.

JOHN STOGDELL STOKES.
